STREET LAMP

Luis F. Villa, 1727 Moravian St., Philadelphia, Pa.

Filed Sept. 21, 1965, Ser. No. 87,095

Term of patent 14 years

(Cl. D48—31)

Fig. 1

Fig. 2

Fig. 3

The support pole in FIGURES 2 and 3 is shown broken away for convenience of illustration. The broken line showing of a base throughout the figures is for illustrative purposes only.

I claim:

The ornamental design for a street lamp, as shown and described.
